UNITED STATES PATENT OFFICE.

CHARLES EDWARD GREEN, OF LONDON, ENGLAND.

CANDLE-LAMP.

1,163,530.

Specification of Letters Patent.

Patented Dec. 7, 1915.

Application filed September 26, 1914. Serial No. 863,726.

To all whom it may concern:

Be it known that I, CHARLES EDWARD GREEN, a subject of the King of Great Britain, residing at London, England, have invented certain new and useful Improvements in Candle-Lamps, of which the following is a specification.

The present invention relates to improvements in candle sticks and particularly to 10 the combination of a vase and candle stick commonly known as a candle lamp.

The object of the invention is to produce a device of the character described with means of a novel and simple construction 15 for adjustably supporting the candle stick in and connecting the latter with the vase in such a manner as to render the same ornamental and effective as a lamp.

With the above objects in view, the invention 20 consists in the provision of a vase adapted to support a candle stick of such a construction as to simulate an ornamental candle, said candle stick consisting of a candle simulating member and of means for 25 supporting a candle therein and out of view; and in a peculiar fastening means for supporting the candle simulating and candle supporting means in position on the vase.

With the above objects in view, the invention 30 further consists in the novel arrangement and combination of parts hereinafter more fully described and finally pointed out in the appended claims.

A device constructed in accordance with 35 the invention is shown in the single figure of the accompanying drawings, partly in section, to clearly illustrate certain detailed construction thereof.

Referring particularly to the drawings, D 40 denotes the vase, which is of any suitable or desired ornamental construction, being provided at its upper end with an opening 1. The candle stick 2 is adapted to be inserted in the opening 1 of the vase D and comprises a sleeve or tube B formed adjacent its 45 upper end with a bead b, and so colored and designed as to simulate a candle. The candle stick 2, also, comprises a candle-containing tube C having one end open and the 50 other end closed, the latter end extending through the opening 1 into the vase D. The candle simulating tube B surrounds or envelops a portion of the tube C extending from the vase D with the exception of its

upper extremity which is capped by the 55 second sleeve F formed with a bayonet or T-slot f adapted to have the projection e co-operate therewith to lock the parts C and F together and in position.

The size of the candle tube C may vary, 60 according to the size of the candle desired to be used; and, also, the candle or simulating sleeve B may vary in size and diameter according to the size and character of the candle desired to be simulated and the size 65 of the candle tube C used in connection therewith. It is preferred to make the candle simulating sleeve B of celluloid, and the sleeve F and the candle tube C of metal, or any other desired non-combustible material. 70

An annular ring or cap E is fitted in the opening 1 of the vase D and overlies the edges of the opening to protect the same. A ferrule A surrounds and frictionally engages the candle tube C, thus permitting the 75 same to be adjusted thereupon. The ferrule is formed with an outwardly extending flange rolled upwardly upon itself to form a resilient bead 5, the purpose of which will be later described.

When the parts of the present invention are assembled, the ferrule A is suitably adjusted on the candle tube C, the end of the tube being inserted in the opening 1 of the vase D and the ferrule A being threaded in 85 the cap E, as shown in the drawings, for securing the candle in the desired adjusted position. The candle simulating sleeve B is also placed around the tube C and has its lower end resting upon the flange of the ferrule A and held into position by the resilient beading 5, as shown in the drawing. The sleeve F is then placed upon the upper end of the tube C and locked in position.

It will thus be seen that by the fastening 95 means consisting of the ferrule A and the cap E a candle stick may be applied and rigidly secured to a vase of any suitable character without injuring or chipping the edges of the vase. It will also be seen that 100 by the construction of the fastening means a simulating tube or sleeve B of any desired length may be used by so adjusting the ferrule B upon the tube C, it being understood that one feature of the invention is the provision of the resilient beading 5 which frictionally engages the candle simulating tube 105 and holds the same in a substantially rigid

position, thus preventing the same from leaning or tilting out of proper position which may be caused by vibration.

Having thus described my invention, it is believed that a full and clear understanding may be had, however, certain changes as to the precise construction, combination and arrangement of parts may be resorted to that fall within the legitimate scope of the 10 appended claims.

What I do claim as my invention is:—

1. A candle lamp comprising, a tube for containing a candle, a base member for holding said tube in position, a candle simulating tube surrounding a portion of said candle-containing tube extending from the base member, a sleeve adapted to surround and be adjustable on said candle-containing tube and to support the candle simulating tube in position, and means on the base member and coöperating with said sleeve for removably securing the latter to the base member.

2. A candle lamp comprising, a vase having an opening in the upper end thereof, a shield frictionally engaging the edges of said opening, a candle containing tube, a ferrule surrounding said tube and in adjustable frictional engagement therewith, one end of 30 said tube being adapted to be inserted in the

opening of said vase and said ferrule being adapted to be threaded in said shield for securing the tube in position, a candle simulating tube surrounding the exposed portion of the containing tube, and means 35 formed on the ferrule for frictionally holding said simulating tube in position.

3. A candle lamp comprising, a vase having an opening in the upper end thereof, a shield frictionally engaging the edges of 40 said opening and being internally threaded, a candle-containing tube adapted to have one end inserted in the opening of said vase, a ferrule surrounding said tube and in slideable adjustable engagement therewith, said 45 ferrule being adapted to be threaded in said shield for securing the tube in position, a candle simulating tube surrounding the exposed portion of the containing tube, and a resilient beading formed on said ferrule 50 and adapted to frictionally engage and hold the simulating tube in position on said containing tube.

In testimony whereof I have hereunto set my hand in presence of two subscribing witnesses.

CHARLES EDWARD GREEN.
